FIG. 1

FIG. 2

FIG. 3

FIG. 5

FIG. 1 is a front elevational view of my new design for tennis shorts showing my new design;

FIG. 2 is a rear elevational view thereof;

FIG. 3 is a side view thereof;

FIG. 4 is a top view thereof; and

FIG. 5 is a bottom view thereof.

The characteristic feature of my design resides in the combination on tennis shorts of a back rounded pocket, the pocket being gathered at the top and leg openings having gathers at the bottom back center edge, all as shown on the drawing.

I claim:

The ornamental design for tennis shorts, as shown and described.
